(57) CLAIM

The ornamental design of a chair with seat and back shell, as shown and described.

DESCRIPTION

FIG. 1 is a front isometric view of the chair with seat and back shell;

FIG. 2 is a front plan view thereof;

FIG. 3 is a back plan view thereof;

FIG. 4 is a left side plan view thereof;

FIG. 5 is a right side plan view thereof;

FIG. 6 is a top plan view thereof; and,

FIG. 7 is a bottom plan view thereof.

The broken lines shown in the drawing views are included for purposes of illustrating environment and form no part of the claimed design.
